DRAIN TRAP

Filed Jan. 6, 1926

2 Sheets-Sheet 2

UNITED STATES PATENT OFFICE.

WILLIAM R. GILLIES, OF CHICAGO, ILLINOIS, ASSIGNOR TO EQUIPMENT SPECIALTIES COMPANY, OF CHICAGO, ILLINOIS, A CORPORATION OF ILLINOIS.

DRAIN TRAP.

Application filed January 6, 1926. Serial No. 79,617.

My invention relates to a drain trap which is particularly suitable for installation upon railway refrigerator cars.

It is the object of my invention to provide 5 a device of this class which is simple in construction, which can be economically manufactured and which has improved means for cleaning whenever the occasion requires.

The further object of my invention is to 10 provide a drain trap of this class in which the cap may be readily rotated and raised from the outside of the car.

Other objects of my invention will appear 15 from the following detailed description 15 wherein reference is made to the accompanying drawings, in which

Fig. 1 is a plan view of the drain trap constructed in accordance with my invention.

Fig. 2 is a vertical sectional view taken on 20 the line 2—2 of Fig. 1.

Fig. 3 is a vertical sectional view showing a modified embodiment of my invention, and

Fig. 4 shows the rod used in raising and 25 rotating the cap in the embodiment shown in Fig. 3.

Similar characters of reference refer to similar parts throughout the several views.

Referring to Figs. 1 and 2, I have shown the drain trap set in the floor 10 of a rail-

30 way refrigerator car, 11 being the drain pan which is usually employed in bulk heads of such cars. The car construction, so far as illustrated in the drawings, is conventional and need not be described in detail. The 35 drain pan 11 is provided with a circular opening 12 around the periphery of which the receptacle or bowl 13 is securely riveted.

The bowl 13 is preferably surrounded by heat insulating material 14. A pipe 15 is 40 centrally fixed in the bowl 13 and preferably extends upwardly into the bowl through its bottom to a little more than half of the height of the bowl. A ring 16 fits loosely around the pipe 15 at the bottom of the bowl

45 and serves as a bearing for a rotatable collar 17 to which one leaf 18^a of a hinge 18 is riveted. The cap 19 is riveted to the other leaf 18^b of the hinge 18, the leaves being connected by the pintle 18^c. The cap is thus 50 mounted for rotating and pivotal motion. Suitable means, such as rivets 20, are provided to prevent upward movement of the collar 17. A stop 21, riveted to the pipe 15, serves as a support for the cap in its lower

position. A strainer plate 22, provided with 55 a plurality of small perforations 22^a and larger perforations 22^b, is formed in two sections which are joined by the hinge 23 which has a pintle 23^a which lies parallel to the pintle 18^c. An eye rivet 24 secured in 60 the top of the cap 19 extends through a spacer 24^b and is riveted to the larger section of the strainer plate. The portion 24^a of the rivet 24 inside the cap 19 is eye shaped and is threaded by a cooperating eye 25^a of 65 the agitating and rotating rod 25. Rod 25 freely extends through an elbow 26, which is riveted to the lower end of the pipe 15, at a boss 26^a which projects inwardly from the pipe so as to prevent water from leaking out 70 along side the rod 25. The lower end of the rod 25 is bent at right angles to form a handle 25^b by which the cap may be raised and rotated. A sheet steel spout 27 may be secured to the lower portion of the elbow 26 75 by ears 27^a which extend through and are bent over slotted lugs 26^b, so as to deflect water and other refuse draining from the refrigerator car away from journal boxes of 80 the car.

In Fig. 3 I have shown a modification which in most respects is similar to that shown in Figs. 1 and 2, with the exception that in this showing the agitating rod is not secured in the device but in use is carried 85 from car to car by the workman who is cleaning the drains of the cars. In Fig. 3 the rivet 24' by which the straining plate and the cap are secured together terminates in an eye 24'^a preferably of much greater 90 diameter than that shown in Fig. 2 so as to readily permit the entrance of the hook portion 28^a of the raising and agitating rod 28. In this embodiment the elbow 29 has a projecting lug 29^a which is hingedly connected 95 to corresponding lugs 30^a formed on an extension 30 which is riveted to the pipe 15. The lower edge of this extension is preferably cut off at an oblique plane and the elbow 29 has an annular recess formed in its 100 upper edge so as to fit over the lower edge of the pipe extension 30. A chute 27 is secured to the lower end of the elbow 29 for the purposes as already described. The elbow 29 is retained in its position as shown in Fig. 105 3 by the action of gravity upon the chute. It, however, may readily be tilted upward as shown in the dotted line position in Fig.

3 so as to permit access to be had to the interior of the pipe 15 to enable the agitating rod 28 to be hooked into the eye of the rivet 24', and the cap rotated and swung on its 5 hinge.

In the use of these drain pipes it is frequently necessary to move the cap in order to agitate the collection of water, dirt, sawdust and other foreign material which naturally collects in the trap, so as to prevent the trap from becoming clogged. This is done by the workmen by merely raising and rotating the agitating rod. The strainer plate being secured to the cap is also agitated and 10 the sawdust and other débris thus shaken from the perforations and top of the plate. The rotatability of the cap and the plate makes the agitation and cleansing operation 15 very thorough, and minimizes the possibility 20 of damage due to a clogged drain trap.

The invention is capable of variation and adaptation in many respects for use in different embodiments without departure from the principles of the invention. I do not 25 restrict myself in any unessential particulars but what I claim and desire to secure by Letters Patent is:

1. In a drain trap, a bowl, a drain pipe, a 30 collar rotatably mounted on said pipe, a drain pipe cap hinged to said collar, and means to rotate said cap and collar.

2. In a drain trap, a bowl, a drain pipe, a 35 collar rotatably mounted on said pipe, a drain pipe cap hinged to said collar, and means to rotate said cap and collar and to swing said cap relative to said collar.

3. In a drain trap, a bowl, a drain pipe, a 40 collar rotatably mounted on said pipe, a drain pipe cap hinged to said collar, and means secured to said cap for rotating said cap and collar.

4. In a drain trap, a bowl, a drain pipe, a 45 collar rotatably mounted on said pipe, a drain pipe cap hinged to said collar, and means secured to said cap for rotating said cap and collar and to swing said cap relative to said collar.

5. In a drain trap, a bowl, a drain pipe 50 extending into said bowl, a strainer plate fitting loosely over said bowl, a collar rotatably mounted on said pipe, a cap hinged to said collar, means to swing and to rotate said cap, and connecting means for causing said

strainer plate to swing and rotate with said cap.

6. In a drain trap, a bowl, a drain pipe 55 extending into said bowl, a strainer plate fitting loosely over said bowl, a cap hingedly and rotatably mounted on said pipe, and a connecting means securing said cap to said plate.

7. In a drain trap, a bowl, a drain pipe 60 extending into said bowl, a collar rotatable on said pipe, a hinge connecting said cap to said collar, a strainer plate fitting over said bowl and formed in two sections joined by a hinge the pintle of which is parallel to the pintle of said first named hinge.

8. In a drain trap, a bowl, a drain pipe 65 leading from said bowl, a cap rotatably and hingedly mounted on said pipe, and a rod secured to said cap and extending through said pipe for swinging and rotating said cap.

9. A trap for refrigerator cars comprising 70 a bowl-shaped receptacle, a drain pipe projecting through the bottom of said receptacle, the upper edge of said pipe terminating short of the upper edge of the receptacle, a collar rotatably mounted on said pipe, a cap 75 hinged to said collar so as to lie above the upper end of said pipe, a stop projecting from the upper edge of said pipe so as to limit the downward movement of said cap, and means to rotate and swing said cap relative to said pipe.

10. A trap for refrigerator cars comprising 80 a bowl-shaped receptacle, a drain pipe projecting through the bottom of said receptacle, the upper edge of said pipe terminating short of the upper edge of the receptacle, a collar rotatably mounted on said pipe, a cap 85 hinged to said collar so as to lie above the upper end of said pipe, a stop projecting from the upper edge of said pipe so as to limit the downward movement of said cap, a hinged strainer plate resting over the top of 90 said receptacle and rigidly secured to said cap, and means to swing and rotate said cap and strainer plate comprising a rod secured 100 to said cap and extending downwardly through said pipe.

In witness whereof, I hereunto subscribe my name this 30th day of December, 1925.

WILLIAM R. GILLIES.
